BACTERIA PLATE CABINET

Merritt C. Hoag, Johnsonville, N. Y.

Application June 28, 1937, Serial No. 150,879

3 Claims. (Cl. 34—21)

This invention appertains to new and useful improvements in means for preparing specimens of bacteria and storing the same safely until ready for laboratory observation.

5 Another important object of the invention is to provide a cabinet structure for facilitating the taking of bacteria specimens wherein means is provided whereby the specimens can be properly identified as they are taken.

10 Still another important object of the invention is to provide an apparatus of the character stated which is simple in construction and not susceptible to the ready development of defects.

These and various other important objects and 15 advantages of the invention will become apparent to the reader of the following specification.

In the drawings:—

Figure 1 represents a top plan view of the cabinet.

20 Figure 2 is a front elevational view.

Figure 3 is a longitudinal vertical sectional view.

Figure 4 is a cross sectional view on the line 4—4 of Figure 1.

25 Figure 5 is a perspective view fragmentarily showing the guide plate.

Figure 6 is a fragmentary perspective view of one of the specimen glasses.

Figure 7 is a perspective view of one of the 30 slides.

Figure 8 is a perspective view of a dipping loop.

Referring to the drawings wherein like numerals designate like parts, it can be seen that the cabinet consists of an elongated structure including the front wall 5, end walls 6—7 and back wall 8.

The cabinet also includes the bottom wall 9 from which rises the partition 10 defining the compartments 11—12. A second partition 13 extends upwardly from the bottom 9 and terminates below the boiler generally referred to by numeral 14. Extending from the upper end of the partition 13 to the end wall 6 is the horizontal wall 14 which forms a continuing chamber 45 15 for the chamber 12.

A substantial distance below the wall 14 is another horizontal wall 16 extending from the partition 13 to the end wall 6, thus defining a compartment 17. Secured to the bottom side of the wall 14 and the top side of the wall 16 are the corrugated strips 18 which serve to hold the specimen glasses 19 in the manner substantially shown in Figure 3.

The front wall 5 of the cabinet is provided with 55 three openings, one for each of the compart-

ments 11, 12 and 17 and these openings are closed by the doors 20, 21 and 22, respectively, hingedly connected to the front wall 5.

The top of the compartment 11 has an opening 23 therein which is normally closed by the closure 24 hingedly secured as at 25 to the top of the compartment 11.

In the compartment 11 is the alcohol lamp 26, while in the compartment 12 is the alcohol lamp 27. By lifting the cover 24, the loop 28 can be 10 heated over the lamp 26. This type of loop 28 has the shank 29 and the handle 30 and is used for picking up, for instance, milk to be deposited on the smear plates 31—32 resting upon the boiler 14. 15

The boiler consists of the box-like structure made up of the bottom wall *a*, the end walls *b* and the side walls *c*, the top wall *e* is provided with a rectangular-shaped opening 33 therein and one end wall *b* is provided with a horizontal 20 slot through which the elongated shutter 34 can be disposed. Numeral 35 represents a depending stop on the top wall *e* at one end of the opening 33.

As is shown in Figure 5, the top surface of the 25 shutter 34 is laid off in rows of squares 36. The rows are arranged in groups of two and over each group can be disposed one of the smear plates 31 and 32. These specimen plates are of conventional design each provided with a marginal edge 30 portion 37.

Guideways 38 are formed on one end of the top plate *e* of the boiler, one for each of the rows of squares 36 and through these guides 38 are slidable the channeled covers 39 each provided 35 with an engageable upstanding lug 40 at one end thereof.

These slides 39 can be moved in the direction of the guides 38 to uncover the squares 36 visible through the specimen plates 31—32 and then as 40 the specimens are placed on the smear plates 31, the slides are pulled over the plates to shield the specimens.

Water is placed in the boiler 14 and is heated by the lamp 21 so that the specimens will dry 45 very quickly after they are taken. After the specimens have been placed on the plates, one specimen for each square visible through the plate, and the specimens have dried on the plates, the plates can be removed from the boiler and 50 placed in the rack compartment 17.

Keepers 41—44 are provided on the front wall 5 for receiving the L-shaped bracket 42 of the shelf 43, this shelf serving as a leaning rest for the attendant.

Furthermore, a suitable bracket 43 can be provided on the back wall of the cabinet for supporting thermometer 44 in upright position.

While the foregoing specification sets forth 5 the invention in specific terms, it is to be understood that numerous changes in the shape, size and materials may be resorted to without departing from the spirit and scope of the invention as claimed hereinafter.

10 Having described the invention what is claimed as new is:—

1. A cabinet structure of the character described comprising a box-like structure having a vertical partition dividing the interior of the 15 box-like structure into a specimen plate racking chamber and a heating unit chamber, and a boiler disposed over the said heating unit chamber, a slide over the said boiler, and rows of marks of equi-distant spaced relation on the said slide.
- 20 2. A cabinet structure of the character described comprising a box-like structure having a vertical partition dividing the interior of the box-

like structure into a specimen plate racking chamber and a heating unit chamber, and a boiler disposed over the said heating unit chamber, a slide over the said boiler, and rows of 5 marks of equi-distant spaced relation on the said slide, and slide members mounted on the cabinet one over each row of marks on the said slide.

3. A cabinet structure of the character described comprising a box-like structure having a vertical partition dividing the interior of the box-like structure into a specimen plate racking chamber and a heating unit chamber, and a boiler disposed over the said heating unit chamber, a slide over the said boiler, and rows of marks of equi-distant spaced relation on the said slide, 10 and slide members mounted on the cabinet one over each row of marks on the said slides, and guides for the slide members, said slide members being operative to uncover the marks of the first-mentioned slide. 15

20 MERRITT C. HOAG.
